UNITED STATES PATENT OFFICE.

JOHN F. HANLON, OF CONCORD, NEW HAMPSHIRE, ASSIGNOR OF ONE-HALF
TO MAURICE B. QUIMBY, OF SAME PLACE.

UNIVERSALLY-MOVABLE SUPPORT FOR MIRRORS, &c.

SPECIFICATION forming part of Letters Patent No. 544,300, dated August 13, 1895.

Application filed October 29, 1894. Serial No. 527,099. (No model.)

To all whom it may concern:

Be it known that I, JOHN F. HANLON, a subject of the Queen of Great Britain, residing at Concord, in the county of Merrimac and 5 State of New Hampshire, have invented certain new and useful Improvements in Universally-Movable Supports for Mirrors or other Objects; and I do hereby declare the following to be a full, clear, and exact description 10 of the invention, such as will enable others skilled in the art to which it appertains to make and use the same, reference being had to the accompanying drawings, and to figures of reference marked thereon, which 15 form a part of this specification.

This invention relates to a universally-movable support especially adapted to uphold a frame which is to contain an object and present it to the observer in various positions, 20 said support being secured to a base or stand which may be removable or a fixture, as circumstances dictate.

The purpose and object of my invention is to produce a support which shall be in itself 25 an ornament for a room and at the same time one which shall uphold a frame to contain preferably a mirror, and likewise be capable of folding up to economize space in packing. This mirror or other object is so mounted that 30 it is capable of assuming any or every position, and further may be reversed, the back, which is to contain some photograph, engraving, or copy of a work of art, being made to take the place of the mirror.

35 The drawings herewith presented illustrate, in Figure 1, a perspective view of a support embodying my invention as a fixture. Fig. 2 is a plan. Fig. 3 is a diametrical transverse section of the mirror and frame. Fig. 4 is a 40 sectional elevation of the ball-and-socket joint, showing one form of construction.

In the present instance my invention is embodied in twin U-shaped arms or yokes 2 3, interconnected by a universal or ball-and- 45 socket joint 4, while the opposite co-operating ends of said yokes are pivotally secured, respectively, to the frame 5, adapted to contain the object, as a mirror, which is to be mounted therein, and a base 6. This base is intended 50 not only to be ornamental in shape, either circular or polygonal in form, but it may be

made of metal, as bronze, and of sufficient size and weight to act as a counterbalance to create a firm and secure base for the entire group of parts. In the present instance this 55 base contains a clock, as will be seen by reference to Figs. 1 and 2; but it may embody some bronze figure of an animal or a person.

In order to enable the yokes to be positioned at any angle with the base or with the 60 frame 5, thumb-screws 7 7' 7² 7³ are supplied and the friction created by them is to be varied as may be desired. If, for instance, this support is to be packed away, the screws are relaxed and the parts 5 6 are swung down 65 into the same horizontal plane as shown in Fig. 2. In this drawing the base is designed to be removable—that is, adapted for a position upon a table, mantel-piece, or elsewhere— 70 while in Fig. 1 a number of ears 8 are attached to the periphery of the base, by means of which it becomes a fixture and is then adapted as a wall-ornament.

In order to enable the yoke 2 to be placed at any angle with respect to the yoke 3, which 75 has limited swinging motion, a ball-and-socket joint is employed, which device is composed of a ball 9 and a socket 10. These two elements are attached firmly to opposite yokes, but on corresponding portions of the same. 80 To enable said parts to be readily disengaged, and at the same time to regulate the friction which is to exist between the ball and the socket to permit the yoke 2 to be maintained at any angle or in any position desired, the following construction is employed: A tubular block or plate 12 is secured to or made to form a part of this yoke at a point centrally of the latter. Interiorly of said block is formed an annular groove 13, adapted to receive a circular bead or rib 14, which engages the same. 85 This bead forms a part of the lower end or neck 15 of the socket 10, which is longitudinally split, as indicated at 16. The bore of the neck of said socket is tapered and screw-threaded 90 and serves to engage a locking screw-threaded bolt 17. Furthermore, this neck portion extends some little distance below the point where the bead 14 is formed. Hence it will be seen that the insertion of the bolt not only 95 spreads the neck portions apart, causing the rib 14 to be held in engagement with the an-

nular groove, but a slight rocking movement is imparted to the elements composing the socket. Hence as the bolt is forced inwardly and the lower ends of the socket are spread apart the socket portions tighten about the ball, the center of oscillation or fulcrum-point being on the bead. By this construction the socket is not only held fast to the yoke, but the friction of said socket about the ball is easily regulated, and the yoke 2 may be set in any plane or at any angle with the base and so remain undisturbed by gravity.

In lieu of interconnecting the parts, as shown in Fig. 2, a preferred construction is illustrated in Fig. 4, whercin the separable portions of the socket are caused to engage a stud 18 interiorly, while the exterior surface of the neck of said socket is screw-threaded and tapered to receive a clamping-nut 19. Hence by removing the nut the two yokes are easily separated, if desired. Conversely by advancing the clamp upon the neck the sectional parts of the socket may be caused to grip the ball with any degree of tightness.

As before premised, one of the purposes of this invention is to provide a support for a mirror or other object, said support to consist of a base which shall consist of some ornamental piece, while the supported object is to be contained within a frame so supported that it is not only adapted to be positioned in any desired plane or at any angle with the base, but likewise may be reversible. This frame (shown at 5) may consist of a central plate 21, inclosed within a border or rim 23 of any desired shape, circular or polygonal, and ornamented or carved. In Fig. 1 this rim is octagonal and the two sides may be similar. In

Figs. 1 and 3 the two sides are unlike. In Fig. 3 the glass is indicated at 20, while the reverse side is adapted to contain a photograph or engraving at 24. This latter is held in the frame by means of an annular rim 25, which is removably attached by screws or otherwise in order that the picture may be changed if it is so wished. Thus by means of this construction the frame may swing upon its pivots and the mirror may be availed of. When not in use the reverse side is turned outwardly and the support then serves as a photograph holder.

What I claim is—

1. The combination with a base, a universally movable frame, twin yokes pivotally attached to said base and frame, and clamping screws in the extremities of the yokes, of an interconnecting joint comprising a ball, a split socket having a sectional tubular stem, and a clamping device adapted to cause the socket to clasp the ball on one yoke, and the stem to engage the opposite corresponding yoke, substantially as stated.

2. In combination with two similar yokes, a separable joint for uniting the same, and comprising a ball secured to one yoke, a stud transversely on the corresponding yoke, a split socket having an exteriorly threaded stem, and a clamping nut which serves to clasp the socket about the ball and the socket stem about the stud, substantially as described. 70

In testimony whereof I affix my signature in presence of two witnesses.

JOHN F. HANLON.
